UNITED STATES PATENT OFFICE.

JOSEPH H. ALLEN, OF CHICAGO, ILLINOIS, ASSIGNOR, BY MESNE ASSIGNMENTS, TO
GENERAL ELECTRIC COMPANY, A CORPORATION OF NEW YORK.

ARC-LAMP.

996,392.

Specification of Letters Patent. Patented June 27, 1911.

Application filed March 16, 1906. Serial No. 306,363.

To all whom it may concern:

Be it known that I, JOSEPH H. ALLEN, citizen of the United States, residing at Chicago, in the county of Cook and State 5 of Illinois, have invented a certain new and useful Improvement in Arc-Lamps, of which the following is a full, clear, concise, and exact description.

My invention relates to an electric arc 10 lamp, and has for its object to protect the carbon-lifting magnet from abnormal currents which would burn out the coils thereof. Considerable difficulty has been experienced heretofore in arc lamps due to such burning 15 out of the feed magnet coils, which is often caused by the clutch member, after being raised by the magnet core to lift the upper carbon and establish an arc, allowing the upper carbon to slip down into engagement 20 with the lower carbon, thereby greatly decreasing the resistance of the circuit and permitting an abnormally heavy current to flow through the lifting magnet.

My invention contemplates the provision 25 of a thermostatic rod expansible upon the passage of an abnormal current through the lifting magnet, adapted to short circuit said magnet, and permit the armature and clutch to drop into position to separate the carbons 30 when the lifting magnet is again energized.

I preferably employ a thermostatic rod connected in series with the feed or lifting magnet, said rod, upon the passage of an abnormally heavy current in the circuit, 35 expanding to close a pair of contacts controlling a short circuit about the lifting magnet, which thereupon releases its core or armature and allows the clutch member to fall into position to grasp the upper carbon 40 and reestablish the arc when the lifting magnet is again energized. The contacts referred to also close at the same time a short circuit about the thermostatic rod, and as soon as the rod cools and contracts, it 45 separates the contacts referred to and opens the short circuits, whereupon the lifting magnet is energized and separates the carbons to reestablish the arc.

A feature of my invention consists in the 50 provision of means adapted to avoid any possibility of the thermostatic rod closing its short circuit in case said rod should be

expanded, due to an abnormally high temperature in the lamp. To this end I employ a thermostat independent of the circuit 55 of the lamp, which permits the first thermostat to respond to an abnormally heavy current in the lamp and close the short circuit, but which prevents the said first mentioned thermostat, when it responds to an abnor- 60 mally high temperature of the lamp, from closing said short circuit.

I will describe my invention more particularly by reference to the accompanying drawings, wherein—

Figure 1 is a front elevation of a lamp equipped with a protecting device for the lifting magnet embodying my invention; Fig. 2 is a longitudinal sectional view of the protective device; Fig. 3 is a plan view thereof; Fig. 4 is a plan view of a modified form of protective device embodying my invention and provided with means for preventing the thermostatic rod from operating its contacts to short circuit the lifting mag- 75 net when the temperature of the lamp is abnormally raised; Fig. 5 is a sectional view 80 on line 5—5 of Fig. 4; and Fig. 6 is a simplified circuit diagram of the lamp shown in Fig. 1.

Similar letters of reference designate like parts throughout the several views.

The lifting magnet *a* of the arc lamp shown in Fig. 1 is provided with the usual armature or core for operating the clutch *b* 85 to separate the two carbons of the lamp. A thermostatic rod *c* of metal is included serially in the circuit of the magnet *a*, and is secured at one end to a post *c'* mounted upon an insulating base *c''*, the other end of said 90 rod being connected to the lower end of a spring arm *c'*, said post and spring arm having suitable terminals upon the under side of the block *c''*. The rod *c* when expanded, due to the passage of an abormal current in 95 its circuit, is adapted to move the spring arm *c'* into engagement with a contact post *c''* and thereby close a short circuit about the lifting magnet *a*, said contacts *c'' c''* when closed also completing a short circuit around 100 the rod *c*.

Referring to Fig. 6, the circuit of the lamp and its protective device will be readily apparent. The normal circuit extends from

the positive terminal of the lamp by way of conductor 1 to the spring arm c^3 , thence to rod c and post c' , through the lifting magnet a to the upper carbon of the lamp, 5 and thence by way of the lower carbon and conductor 2 to the negative terminal of the lamp. When no current is passed through the lamp, the carbons are in contact, as shown, but when the circuit above referred 10 to is completed, the magnet a is energized and draws up its core or armature, which operates the clutch b shown in Fig. 1, to separate the carbons and establish an arc. Now, if for any reason the clutch should accidentally 15 release the upper carbon while the core is attracted and allow the upper carbon to fall into engagement with the lower carbon, the arc would no longer be present and the resistance of the circuit greatly decreased, whereupon the abnormally heavy current would flow through the circuit 1, 2 and, if permitted to flow for any length of time would burn out the coils of the magnet a . The thermostatic rod c , being in the 25 circuit, is heated and expanded by this abnormally heavy current, and moves the spring arm c^3 into engagement with the contact post c^4 , which is connected by conductor 3 with conductor 1, between the magnet a 30 and the upper carbon, thereby short circuiting the magnet a , which allows its core together with the clutch, to fall into position to lift the upper carbon when the magnet a shall again become energized. The contacts 35 $c^3 c^4$ when closed also short circuit the rod c by way of conductor 3, and rod c is allowed to cool. When cooled, the rod contracts and separates the contacts $c^3 c^4$, breaking the short circuit referred to and permitting current 40 to flow through the magnet a , which draws up its core and separates the carbons to reestablish the arc. The rod c is preferably adjustably secured to the post c' , so that the distance between the contacts $c^3 c^4$ 45 may be varied as desired, the rod c of course being rigidly secured to the spring arm c^3 . Such adjustment may be secured in the manner most fully shown in Figs. 2 and 3 in which the rod c passes through or is otherwise 50 secured to a set screw c^5 , said set screw being adjustable in the post c' .

In order to prevent any possibility of an abnormally high temperature of the lamp caused by the heat of the arc, from heating 55 and expanding the thermostatic rod and closing the contacts $c^3 c^4$, I may employ the type of protective device shown in Figs. 4 and 5, which is provided with means for rendering the rod c ineffectively responsive 60 to such an abnormally high temperature.

I provide a rocking lever d connected at one side d' of its pivot with one end of the thermostatic rod c , the other end of said rod being connected with a spring member e . A 65 second thermostatic rod f is connected at

one end with the lever d at the other side d'' of its pivot, being insulated therefrom by a suitable bushing, and the other end of said rod f is connected with the spring member e . The lever d is provided with a suitable terminal underneath its supporting base, which would be connected with conductor 1 in the manner of spring arm c^3 shown in Fig. 6, and the spring member e is provided with a similar terminal connected with conductor 70 1 in the manner of supporting post c' of Fig. 6. An extension d^4 of the lever d , which preferably lies parallel with the rods c, f , is provided with a normally-open contact d^5 with which it is adapted to engage 75 when the lever d is rocked by the expansion of the rod c , these contacts $d^4 d^5$ corresponding to the contacts $c^3 c^4$ shown in Fig. 6.

When an abnormally heavy current passes through the rod c and the magnet a , the rod c is heated and expands, rocking the lever d to close the contacts $d^4 d^5$. Since no current passes through the rod f , it will not be expanded and will coöperate with the spring member e to permit the rocking lever d to close contacts $d^4 d^5$. In case, however, an abnormally high temperature is present in the lamp, both rods c, f will be expanded and will move the spring member e to the left 80 without, however, affecting the lever d .

I claim:—

1. In an electric arc lamp, the combination with an arc-controlling magnet, of a circuit therefor, a thermostatic rod in said circuit adapted to respond to an abnormal current therein, a rocking lever connected at one side of its pivot with one end of said rod, a spring member to which the other end of said rod is connected, a short circuit about said magnet closed by said lever when rocked by the expansion of said rod, and a thermostatic rod connecting said lever at the other side of its pivot with said spring member to prevent the closure of said short circuit when the lamp temperature is abnor- 100 mally raised.

2. In an electric arc lamp, the combination with an arc-controlling magnet, of a circuit therefor, a thermostatic rod in said circuit responsive to an abnormal current therein, a rocking lever connected at one side of its pivot with one end of said rod, a spring lever to which the other end of said rod is connected, an extension of said arm, 105 a normally-open contact adapted to be engaged by said arm when said lever is rocked by the expansion of said rod, a short circuit about said magnet closed by said extension and its contact, and a thermostatic rod insulated from said lever and connecting the same at the other side of its pivot with said spring member, both of said rods expanding upon an abnormal increase in the lamp temperature to prevent rocking of said lever.

3. In an electric arc lamp, the combina- 115 120 125 130

tion with an arc-controlling magnet, of a circuit therefor, a rocking lever adapted when operated to close a short circuit about said magnet, and a pair of thermostatic rods, one of said rods being included in said circuit to respond to abnormal currents and operate said lever, both of said rods operating in response to any abnormally high

temperature of the lamp to prevent the operation of said lever.

In witness whereof, I hereunto subscribe my name this 13th day of March A.D. 1906.

JOSEPH H. ALLEN.
